239,020

VALVE ACTUATOR FOR A URINARY DRAINAGE BAG OR THE LIKE

James Gordon Manschot, Mukwonago, Wis., and Kenneth Howard Knox and Robert Dyall Flinn, Libertyville, Ill., assignors to Abbott Laboratories, North Chicago, Ill.

Filed Feb. 25, 1975, Ser. No. 552,920

Term of patent 14 years

Int. Cl. D23—01

U.S. Cl. D23—19

FIG. 1.

FIG. 2.

FIG. 3.

FIG. 1 is a perspective view taken from one end of a valve actuator for a urinary drainage bag or the like showing our new design;

FIG. 2 is a perspective view taken from the end opposite that shown in FIG. 1; and

FIG. 3 is a side elevational view thereof.

We claim:

The ornamental design for a valve actuator for a urinary drainage bag or the like, substantially as shown.
